(57) **CLAIM**

The ornamental design for endurance tester for flexible display, as shown and described.

DESCRIPTION

The patent or application file contains at least one drawing executed in color. Copies of this patent or patent application publication with color drawing(s) will be provided by the Office upon request and payment of the necessary fee.

1.1 : Perspective

1.2 : Front

1.3 : Back

1.4 : Left

1.5 : Right

1.6 : Top

1.7 : Bottom

The elements colored in yellow are included for the purpose of illustrating portions of the endurance tester for flexible display that form no part of the claimed design.
